UNITED STATES PATENT OFFICE

154,534

DESIGN FOR A COMBINED ADVERTISING DISPLAY AND CLOCK

Charles L. Dwinell, Kansas City, Mo.

Application May 5, 1948, Serial No. 146,180

Term of patent 14 years

(Cl. D1—12)

To all whom it may concern:

Be it known that I, Charles L. Dwinell, a citizen of the United States, residing at Kansas City, in the county of Jackson and State of Missouri, have invented a new, original, and ornamental Design for a Combined Advertising Display and Clock, of which the following is a specification, reference being had to the accompanying drawing forming a part thereof, wherein:

Fig. 1 is a front elevational view of a combined advertising display and clock, showing my new design.

Fig. 2 is a side elevational view thereof.

Fig. 3 is a top plan view thereof.

The back of the device is plain and without ornamentation.

I claim:

The ornamental design for a combined display and clock, as shown and described.

CHARLES L. DWINELL.
